HIGH-OUTPUT FLUORESCENT LAMP HAVING MEANS FOR MAINTAINING A PREDETERMINED MERCURY VAPOR PRESSURE DURING OPERATION

Daniel A. Larson, Cedar Grove, and Grant W. Manning, Jr., Denville, N.J., assignors to Westinghouse Electric Corporation, East Pittsburgh, Pa., a corporation of Pennsylvania

Filed June 23, 1961, Ser. No. 119,230
11 Claims. (Cl. 313—34)

This invention relates to electric discharge devices and, more particularly, to fluorescent lamps of the high output or so-called "highly-loaded" type.

In order to provide more light at lower cost and maintenance there have recently been developed so-called "high output" fluorescent lamps which have a much higher loading than lamps of conventional design. The term "loading" refers to the number of watts per unit of lamp length. Thus, a standard 40 watt fluorescent lamp 4 foot in length is said to have a loading of 10 watts per foot. Fluorescent lamps of conventional design having a loading as high as 16 watts per foot are known but are relatively inefficient as compared to lamps having a normal loading of 10 watts per foot and thus have not been widely adopted, at least not in this country. The high output lamps now being marketed have loadings as high as 25 watts per foot.

As is well known, a conventional fluorescent lamp cannot be converted into a high output lamp simply by increasing the power input and thus increasing its loading. The reason for this is because the lamp efficiency decreases as the current density increases. Various means have been employed to compensate for the drop in efficiency at high loadings, such as the use of indentations or grooves in the lamp envelope that increase the ion losses to the walls, and the use of lighter fill gases such as neon that increases the mobility of the mercury ions—both of which increase the diffusion losses and the electron temperature. This increase in electron temperature, in turn, increases the efficiency with which ultraviolet (UV) radiations are produced within the discharge and, thus, the lamp efficiency.

In addition to having a commercially acceptable efficiency, a high output fluorescent lamp must also have a satisfactory lumen maintenance during life. The substitution of lighter fill gases such as neon for the usual argon fill has aggravated the problem of lumen maintenance insofar as sputtering occurs at a much faster rate resulting in a more pronounced blackening of the envelope. The use in the prior art highly-loaded lamps of a T12 (1½ inch diameter) bulb with a lighter gas fill has further aggravated the maintenance problem because of the more intense blackening of such relatively small bulbs. In the case of the "grooved" high output lamp, a larger T17 (2½ inch diameter) envelope is employed. However, since the loading per unit area of envelope is not uniform because of the grooves, the same problem with regard to efficiency and maintenance prevail.

It is accordingly the general object of this invention to provide a high output fluorescent lamp that can be conveniently and inexpensively manufactured and which has a higher efficiency and better lumen maintenance than prior art lamps of the same loading.

The aforesaid object of the invention, and others which will become apparent as the description proceeds, are achieved by providing a fluorescent lamp having a fill gas and bulb size such that the operating temperature for optimum UV generation and efficiency is considerably below that heretofore considered standard for fluorescent lamps. Specifically, a neon or neon-rich fill gas and a

2

T17 envelope are combined according to a preferred embodiment of the invention to provide a high output lamp that not only has a higher efficiency but better lumen maintenance during life than the prior art lamp designs.

5 With this combination the operating temperature for optimum mercury vapor concentration is about 35° C. instead of the usual 40–45° C. Means for maintaining a region within the lamp that has the aforesaid lower operating temperature is also provided.

10 A better understanding of the invention will be obtained by referring to the accompanying drawing, wherein:

FIGURE 1 is an elevational view of a high output fluorescent lamp that incorporates this invention, a part of the envelope being omitted for convenience of illustration;

15 FIG. 2 is a graph illustrating the relationship between the voltage-versus-current characteristics and the bulb diameter for a plurality of fluorescent lamps of conventional loading and design;

20 FIG. 3 is a graph illustrating the relationship between the fill gas composition and the relative efficiency and brightness of highly-loaded lamps embodying the invention;

25 FIG. 4 is a graph illustrating the relationship between the lamp wattage and the fill gas composition of the improved lamps; and

FIG. 5 is a graph illustrating the relationship between the end chamber temperature and the relative efficiency and brightness for a representative lamp incorporating 30 the invention.

While this invention can be advantageously employed to improve the efficiency and maintenance of various kinds of discharge lamps, it is particularly adapted for use in conjunction with high output fluorescent lamps and has accordingly been so illustrated and will be so described.

In FIG. 1 there is shown a highly-loaded fluorescent lamp 10 embodying this invention which lamp generally comprises a tubular light-transmitting envelope 12 that is provided at each end with the usual bases 13 and 14. Mount assemblies 15 and 16 are sealed to each end of the envelope and support oppositely disposed thermionic electrodes 17 and 18, such as tungsten coils that have been coated with a suitable electron-emissive material such as the well-known mixture of alkaline earth oxides, for example. The inner surface of the envelope is coated with phosphor 22 that converts the UV radiation generated within the discharge into visible light. The envelope also contains the usual charge of mercury 20 and an inert ionizable fill gas. The fill gas in accordance with this invention comprises 100% neon, or a pre-selected mixture of neon and argon, at a preselected pressure, as hereinafter disclosed.

55 Suitable cooling means for controlling the mercury vapor pressure is provided, such as heat-deflecting shields 23 and 24 that are held in transverse relation with respect to the lamp axis by the mount assemblies 15 and 16. The shields may be fabricated from a suitable metal such as nickel and are of such diameter that they provide a 60 cooling chamber of predetermined length L at each end of the lamp 10.

As shown in FIG. 2, the character of a mercury-rare gas discharge is such that for a given lamp design and current density the lamp voltage inherently decreases as 65 the diameter of the envelope increases. Thus, at a relative current density of about 50 a T8 lamp has a rating of about 145 volts (as shown by curve 26), a T12 lamp a rating of about 95 volts (curve 28), and a T17 lamp a rating of about 65 volts (curve 30). The lamps from which these curves were obtained were lamps of conventional loading and design filled with 2 mm. argon operated at an ambient of 40° C. On the basis of such

data it was the general belief heretofore that T17 tubing was not desirable or practical for use in making highly-loaded lamps because of the low voltage gradient and low efficiency which would normally result.

However, it has been discovered that envelopes having a diameter greater than 1½ inches (T12) up to and including a T17 (2½ inches) size cannot only be employed in high output fluorescent lamps but that a higher efficiency and better lumen maintenance will be obtained—providing the proper fill gas and pressure are used and a cooling chamber of sufficient size is employed. Specifically, it has been found that a T17 high output lamp of superior maintenance and efficiency can be obtained in accordance with this invention by using a filling of 100% neon, or a mixture of neon and argon which contains at least 80% neon, and a fill pressure of between about 0.5 and 2.5 mm. of mercury, and preferably from about 1.5 to 2.5 mm. For optimum efficiency and brightness the fill pressure should be about 2 mm.

For some reason which is not perfectly understood the aforesaid combination of a T17 envelope and a specific fill gas composition and pressure lowers the temperature required for optimum mercury vapor pressure and UV generation by about 5–10° C. That is, instead of maximum efficiency occurring at an operating temperature of 40–45° C., as in the case with conventional and other types of high output lamps, the T17 lamp 10 of the present invention operates most efficiently when there is a region within the lamp that has a normal operating temperature of from about 30 to 35° C.

According to the illustrated embodiment of the invention, the required lower operating temperature for optimum efficiency is obtained by correlating the diameter D of the envelope 12 and the length L of the cooling end chamber. In the specific example of a T17 bulb here illustrated where D is 2½ inches, it has been found that a cooling chamber having a length L of 7 centimeters provided the required lower temperature and maintained the mercury vapor pressure at the correct value when the lamp was operated at its rated loading. The lamp in this case had an overall length of 4 feet and operated at 100 watts, that is, at a loading of 25 watts per foot.

As is shown by the solid line curve 32 of FIG. 3, the brightness or light output of the aforesaid T17 lamp decreases as higher concentrations of argon are added to the neon fill gas. However, as indicated by the dotted-line curve 34, the efficiency slowly increases as small amounts of argon are added, reaches a maximum at about 90% neon-10% argon, and then rapidly decreases with higher concentrations of argon. The fill gas, accordingly, consists of 100% neon, or a mixture of neon and argon wherein neon constitutes at least 80% of the mixture, and preferably from about 85 to 95% thereof. The lamps on which these curves are based were 100 watt T17 lamps 4 foot long having an end chamber temperature of approximately 35° C. and a fill pressure of 2 mm. Points A and B designate the efficiency and brightness, respectively, of a lamp of the same construction but with a conventional 100% argon fill at 3.4 mm. of pressure. From FIG. 3 it will be seen that at the prescribed lower operating temperature, a highly-efficient T17 lamp having a loading of 25 watts per foot can be provided which will operate at optimum efficiency when the fill gas comprises a neon-argon mixture in the ratio of approximately 9/1.

As shown in FIG. 4, the wattage of a T17 lamp of the same design as described above decreases rather rapidly from a maximum when 100% neon is used as the fill gas and then begins to level out when the fill gas comprises a 9/1 mixture of neon and argon. With respect to maximum wattage and brightness, optimum results will accordingly be realized with 100% neon, or a mixture of neon and argon wherein the argon is present in only very small amounts. In contrast, a T17 of the same construction but having a conventional 100% argon fill at 3.4 mm.

pressure operates at a much lower wattage as indicated by point C in FIG. 4.

As will be noted from the dotted-line curve 38 of FIG. 5, when a 90% neon-10% argon gas mixture at 2 mm. pressure is employed in the T17 highly-loaded lamp of this invention the efficiency is at a maximum when the end chamber temperature is about 34 or 35° C. Moreover, as is evident from the solid line curve 40, the brightness or light output is at a maximum when the end chamber temperature is about 31 to 32° C. Thus, both the efficiency and brightness are at a maximum at approximately the same end chamber temperature and mercury vapor pressure. This is rather surprising since this is not the case in any other highly-loaded lamp, or any other type of fluorescent lamp for that matter.

As an example of the order of improvement attainable with highly-loaded lamps embodying this invention, the light output and efficiency as well as the power factor of a 4 foot T17 lamp having an 87% neon-13% argon fill are compared below in Table I with a prior art T12 80% neon-20% argon highly-loaded lamp after 100 hours burning. In each case, the lamps had end chambers at both ends 7 centimeters long and were provided with heat shields behind the electrodes.

TABLE I

Lamp Construction	Current, amps	Volts	Watts	Lumens	Eff., LPW	Power Factor
T12, 80 Ne-20 Ar T17, 87 Ne-13 Ar	1.5 1.5	86 75	109 102	7,200 7,350	66 72	85 91

As will be seen from the foregoing table, the highly-loaded lamp having a neon-rich fill gas mixture, a T17 envelope and a lower optimum operating temperature in accordance with this invention not only produces more lumens and has a higher efficiency than the prior art lamp but also has a higher power factor, which latter feature is desirable since the actual lamp wattage is accordingly proportionately higher. Zero hour readings of the test lamps has shown that the drop in light output of the improved T17 lamps dropped about 2 to 3% after 100 hours burning whereas a 9% drop occurred in the case of the prior art T12 lamps. Thus, a T17 highly-loaded fluorescent lamp having the specific design features hereinbefore described is superior in both efficiency and lumen maintenance in comparison to conventional highly-loaded lamps having bulbs of smaller diameter.

It will be obvious that the lower operating temperature required for optimum efficiency can be obtained by means other than cooling end chambers. For example, thermoelectric cooling can be employed in the manner disclosed in U.S. Patent No. 2,932,753.

It will be apparent from the foregoing that the object of the invention has been achieved insofar as a highly-loaded fluorescent lamp has been provided which not only exhibits an improved efficiency and lumen maintenance during life but which can be very easily and economically fabricated insofar as it does not require an envelope of complex configuration.

While a specific lamp embodiment has been illustrated and described in detail by way of example, it will be appreciated that various modifications therein and in the fill gas component can be made without departing from the spirit and scope of the invention.

We claim:

1. A low-pressure electric discharge lamp adapted to be operated at a predetermined wattage loading and comprising; a tubular radiation-transmitting envelope containing a pair of spaced electrodes, an ionizable medium within said envelope consisting of mercury and a fill gas selected from the group consisting of neon and a mixture of neon and argon wherein neon constitutes at least about 80% of the mixture, the pressure of said fill gas being from about 0.5 to 2.5 mm., and means asso-

ciated with said lamp for providing a cool region therein, the diameter of said tubular envelope at said cool region being so correlated relative to the cooling ability of said cooling means that the latter provides a location within said lamp that has a temperature of from about 30 to 35° C. when the lamp is operated at said loading.

2. An electric discharge lamp as set forth in claim 1 wherein said fill gas is 100% neon.

3. An electric discharge lamp as set forth in claim 1 wherein said fill gas consists of a mixture of neon and argon containing at least 80% neon.

4. A high-output low-pressure discharge lamp comprising; a tubular radiation-transmitting envelope having a diameter greater than 1½ inches, a thermionic electrode at each end of said envelope, a charge of mercury and an ionizable fill gas sealed within said envelope, said fill gas comprising essentially neon at from about 1.5 to 2.5 mm. pressure, and means integral with said lamp providing a cooling chamber therein, said lamp a predetermined wattage rating and the dimensions of said cooling chamber and the diameter of said envelope being so correlated that there is provided within said chamber a region having a temperature of from about 30 to 35° C. when the lamp is operated at its rated wattage.

5. A fluorescent lamp adapted to be operated at a loading in excess of 16 watts per foot and comprising; a tubular envelope having a diameter of approximately 2½ inches, a phosphor coating on the inner surface of said envelope, a thermionic electrode at each end of said envelope, a contained charge of mercury and an inert ionizable fill gas, said fill gas comprising essentially neon at from about 1.5 to 2.5 mm. pressure, and a cooling chamber at one end of said envelope, the length of said cooling chamber being so correlated with respect to the envelope diameter that there is provided within said chamber a region that has a temperature of from about 30 to 35° C. when the lamp is operated at said loading.

6. A fluorescent lamp as set forth in claim 5 wherein said fill gas consists of a mixture of approximately 90% neon and 10% argon at about 2 mm. pressure.

7. A fluorescent lamp as set forth in claim 5 wherein said fill gas consists of 100% neon at a pressure of about 2 mm. of mercury.

8. A low pressure electric discharge lamp adapted for operation at a predetermined wattage loading and comprising; a radiation-transmitting envelope containing a pair of spaced electrodes and a predetermined quantity of mercury, an ionizable fill gas including at least 80% neon sealed within said envelope, the pressure of said fill gas being from about 0.5 to 2.5 mm., and means adapted in conjunction with the cooling effect produced by the size of said envelope to provide a cool region within said envelope that has a temperature between about 30 and 35° C. when the lamp is operated at said wattage loading.

9. An electric discharge lamp as set forth in claim 1 wherein said cooling means comprises an energizable thermoelectric member.

10. A fluorescent lamp adapted for operation at a loading greater than 16 watts per foot comprising; a tubular envelope having a diameter of approximately 2½ inches, a thermionic electrode at each end of said envelope, a predetermined quantity of mercury and an ionizable fill gas comprising neon containing up to 20% argon sealed within said envelope, the pressure of said fill gas being from about 0.5 to 2.5 mm., and a heat-deflecting shield located between one of said electrodes and the proximate end of said envelope at a point such that it defines, together with the encircling end portion of said envelope, a cooling chamber that is approximately 7 centimeters long and 2½ inches in diameter and is adapted by virtue of its size to provide a region within said envelope that has a temperature of from about 30 to 35° C. when the lamp is operated at said loading.

20 11. A fluorescent lamp adapted for operation at a loading greater than 16 watts per foot comprising; a tubular envelope having a diameter of approximately 2½ inches, a thermionic electrode supported by a mount assembly at each end of said envelope, a predetermined quantity of mercury and an ionizable fill gas comprising at least about 90% neon at a pressure of about 2 millimeters sealed within said envelope, and a heat-deflecting shield on one of said mount assemblies and supported thereby in transverse relation with respect to the longitudinal axis 25 of said envelope at a point located between the proximate electrode and the end wall of the envelope such that it defines, together with the encircling end portion of said envelope, a cooling chamber that is approximately 7 centimeters long and 2½ inches in diameter and is adapted by 30 virtue of its size to provide a region within said envelope that has a temperature of from about 30 to 35° C. when the lamp is operated at said loading.
